COMBINED WELDER'S SHIELD AND SUPPLY CONTAINER

Harold S. Grace, New Orleans, La.

Application May 14, 1943, Serial No. 487,030

5 Claims.

(Cl. 206—1)

This invention relates to a combined welder's shield and supply container.

One of the objects of the invention is to provide means for efficiently confining the arc rays caused in welding, to protect nearby co-workers and passers-by from eye flash and the like.

A further object of the invention is to provide a readily portable and compactly arranged container for the necessary supplies and equipment used by a welder, thereby facilitating the welder's movements up and down ladders and the like, and also enabling him to carry sufficient materials and tools to insure against unnecessary loss of time to replenish his supplies.

A further object of the invention is to encourage at all times the proper disposition of tools and equipment whereby likelihood of injury to others by falling tools and the like, and also whereby loss of or damage to the tools and equipment are minimized.

A further object of the invention is to provide suitable and adequate storage space for unused welder's rods and for the stubs of used rods so that a ready check may be had as to the number of rods used by a welder during a period of duty.

Many other objects and advantages may become apparent to craftsmen and manufacturers using the combined shield and container.

In the accompanying drawings:

Figure 1 is a perspective view showing a combined shield and container in accordance with this invention in applied position.

Figure 2 is a top plan of the combined shield and container.

Figure 3 is a vertical section taken on the line 3—3 of Figure 2.

Figure 4 is a vertical section taken on the line 4—4 of Figure 2.

Figure 5 is a horizontal section taken on the line 5—5 of Figure 3.

Figure 6 is a detail perspective of the insulating liner for a rod compartment.

Referring to the drawings in detail, the numeral 1 designates a base member substantially U-shaped in cross section adapted to be placed in front of a welder to provide a confined work area from which there is no appreciable likelihood of eye flash to anyone in the immediate vicinity, and to provide a support for a plurality of material and equipment housing elements. The base member 1 is provided on its inner face with a heat insulating lining 2 which also extends across the lower edge of the base member. The lining 2 protects the base member 1 from injury during the actual welding operation

and also immediately thereafter by contact with the welded seam.

The front central portion of the base member 1 is provided with a top wall 3 for obstructing upwardly directed rays, and secured to the top wall is a handle 4 by means of which the shield may be readily moved or carried as desired. Also secured to the base member 1 is a pair of spaced lugs 5 which may be engaged by any suitable connecting element such as a rope for suspending the shield from the body of the user should it be desirable to transport the shield while leaving the hands free.

Adjacent each vertical rear edge thereof, the base member provides the inner wall of a rod supply compartment 6, the outer wall of which consists of a housing member 7 preferably curved in cross section suitably secured to the base member 1 and having an open side adjacent thereto which is closed by the inner wall forming base member 1. The housing element 7 is provided with a permanent bottom 8 and a cover 9 which is hinged or otherwise removable. Preferably the base 1 is of slightly greater height adjacent its rear edges so that the compartments 6 will project the plane of the base at the center of the latter. Both of the compartments 6 may be used for storing unused rods, replacing them as they are used with stubs, or if desired, one of the compartments may be used for unused rods, and the other for the stubs of used rods. Each compartment is provided with a heat insulating liner 10 conforming thereto in size and shape and having an open top but otherwise closed to protect the walls of the compartment from injury in the event a heated rod or stub is placed therein.

Suitably secured to the front face of the base 1 is a housing element 11 which cooperates with the base member to form a glass holder. Also secured to the front wall of the base is a loop forming strap 12 for mounting a welder's hammer, and a similar strap 13 for mounting a welder's brush. Carried by the housing element 11 is a hook 14 for supporting a mask such as 15 when not in use.

In the use of a combined shield and supply container in accordance with this invention, a supply of welder's rods is placed in one or both of the compartments 6, the glass holder is provided with a supply of glasses such shown at 16, the welder's hammer, brush and mask are placed in position, and all carried as a unit to the place of operation where the base is placed in position with respect to the work so as to confine the arc

rays to the open rear occupied by the welder. The unit may be readily moved from place to place either by means of the handle 4 or by any suitable carrying element secured to the lugs 5.

I claim as my invention:

1. A combined shield and supply container unit for welders comprising a base member having a closed front and sides and a partially closed top, the bottom and rear thereof being open, and a housing element secured to each side of the base adjacent the open rear thereof to provide the outer and bottom walls of a rod compartment, the inner wall of which is formed by the adjacent side portion of the base.

2. A combined shield and supply container unit for welders comprising a base member having a closed front and sides and a partially closed top, the bottom and rear thereof being open, a housing element secured to each side of the base adjacent the open rear thereof to provide the outer and bottom walls of a rod compartment, the inner wall of which is formed by the adjacent side portion of the base, and a heat insulating lining for each rod compartment and for the inner face of the base.

3. A combined shield and supply container unit for welders comprising a base member having a closed front and sides and a partially closed top, the bottom and rear thereof being open, a housing element secured to each side of the base adjacent the open rear thereof to provide the outer

and bottom walls of a rod compartment, the inner wall of which is formed by the adjacent side portion of the base, and a heat insulating lining for each rod compartment and for the inner face of the base, the lining for the base extending across the lower edge thereof, and the lining for each rod compartment conforming in size and shape thereto and having an open top.

5 4. A combined shield and supply container unit for welders comprising a base member having a closed front and sides and a partially closed top, the bottom and rear thereof being open, and a housing element secured to each side of the base adjacent the open rear thereof to provide the outer and bottom walls of a rod compartment, the inner wall of which is formed by the adjacent side portion of the base, the base member providing a support for mounting the essential equipment of a welder.

10 5. A combined shield and supply container unit for welders comprising a base member having a closed front and sides and a partially closed top, the bottom and rear thereof being open, a housing element secured to each side of the base adjacent the open rear thereof to provide the outer and bottom walls of a rod compartment, the inner wall of which is formed by the adjacent side portion of the base, and supporting means at the top of the base for carrying the unit.

HAROLD S. GRACE.
